UNITED STATES PATENT OFFICE.

JOSEPH E. WATTS, OF LAWRENCE, MASSACHUSETTS.

IMPROVEMENT IN STEAM-TRAPS.

Specification forming part of Letters Patent No. **88,103**, dated March 23, 1869.

To all whom it may concern:

Be it known that I, JOSEPH E. WATTS, of Lawrence, in the county of Essex and Commonwealth of Massachusetts, have made an invention of a new and useful or Improved Automatic Steam-Trap; and I do hereby declare the following to be a full, clear, and exact description thereof, due reference being had to the accompanying drawings, making part of this specification, and in which—

Figure 1 is a vertical and central section, and Fig. 2 a horizontal section, of my invention.

It is presumed that all intelligent mechanics—and to such persons this specification is chiefly addressed—are familiar with the purposes of a "steam-trap," as it is generally termed, that is to allow of the discharge of condensed water resulting from the condensation of steam without loss or escape of such steam.

My invention relates to means for accomplishing the above purpose in a simple and effective manner, and certain minor details in construction, from which advantages result of sufficient importance to make my invention valuable as compared with most, if not all, others now in use.

The invention consists in the employment of an attenuated pipe or shell, provided in a suitable manner with a valve-seat at bottom, and at its upper part properly prepared for connection with any object containing condensing steam, the interior of such pipe containing a tube or rod composed of a more expansive metal than itself, and carrying a valve at bottom to shut upon the valve-seat before mentioned, the upper portion of said valve-rod extending through the top of the outer tube, or a stuffing-box applied thereto, and being depressed toward the valve-seat by a spring suitably applied, such spring acting, in conjunction with a regulating gage or stop, in such manner as to vary the distance of the valve from its seat, according to varying conditions of locality and the metal employed, it being necessary to the successful operation of my invention that the length of the valve-rod with respect to its case shall be such that in its longest condition it shall close the valve-port and in its shortest condition shall remain some distance above such port, or sufficiently so to al-

low of easy escape of water thereby, the whole being as hereinafter explained.

In the drawings before alluded to as accompanying this specification, and which illustrate my invention, A denotes a pipe, cylinder, or casing of somewhat attenuated length, such casing being composed of iron, as being cheap of production, and to a great extent of little comparative expansive properties, the lower extremity of such casing being provided in any suitable manner with a valve-seat, a, and outlet b for permitting of exit of water therefrom. Toward its upper end the casing A is formed with an inlet opening or pipe, c, for permitting entrance of steam and water, while above such inlet c, and at its extreme upper end, the casing A is provided with a stuffing-box, d.

B in the drawings denotes the valve-rod, being in this instance, to increase its radiating and absorbing area or surface, preferably composed of a tube, the metal of such valve-rod B being of a more expansive nature than its surrounding case. The valve-rod B is provided at its lower end with a valve, e, to operate in conjunction with the valve-seat a, before mentioned, and passes upward through the stuffing-box d, as represented, the purpose of the latter, as will at once be understood, being to prevent passage of steam or water about the valve-rod and from the case A at this point.

C denotes an annular inverted cup, secured upon the valve-rod and surrounding the upper part of the stuffing-box and its cap, such cup resting upon the top of the case A, and by this means determining the relative positions of the valve and its seat. A check-nut, f, is screwed upon the valve-rod and down upon the cup c to prevent rotation of the latter upon the former, while immediately above the said check-nut f, and upon the upper end of the rod, a second nut, g, is secured, a small space intervening between the two.

D is a bent and yoke-shaped spring spanning the top of the case A and cup c, and secured to opposite sides of such case, the said spring pressing upon the upper nut, g, with considerable force, and as a consequence, depressing the valve-rod and forcing its attached cup c to a bearing upon the top of the case A, as before premised.

The device is to be so disposed with respect

to an object containing steam as to allow of free entrance of the condense-water to the interior of the case through its inlet or orifice *c*. As the condense-water collects within and partially or wholly fills the case *A* it parts with its latent heat, and as the temperature is reduced its effect upon the valve-rod is such as to contract the same to a greater extent than the case *A*, by this means raising the valve *e* from off its seat and allow the water to escape through the outlet-port *b*, or to be driven through it by pressure of the steam upon or against it. In this way the interior of the case *A* is emptied, or nearly so, of its contents of water, which is replaced by steam, which follows the retreat of such water. The high comparative temperature of the steam expands the body or surface of the valve-rod in excess of that of the case *A* to such a degree as to lower the valve upon the seat *a* and prevent escape of steam through the latter. The closing of the valve allows the condense-water to accumulate within the case *A* until it acquires sufficient body and arrives at the proper temperature to contract the valve-rod and open the port in manner and with results first explained.

The adjustment of the length of the valve-rod, and consequently the relative position of the valve and seat, would be a work of considerable time, and varying with changing conditions of metal and locality, were it not for the employment of the gage or regulating cup or disk *c*, as operated by the spring *D* or its equivalent, as stated.

The whole device is simple and cheap of construction, and is effective in any position or locality in which it may be applied, and, as before premised, allows automatically the escape of condense-water without the loss of any appreciable amount of steam.

What I claim as my invention, and desire to secure by Letters Patent, is—

The arrangement, with the outer case, *A*, its inlet and outlet ports and valve-seat, of the valve-rod and valve within said case, and the gage and spring for actuating and controlling said valve-rod, substantially as shown and set forth.

JOSEPH E. WATTS.
